John O. Grady, Arab, Ala.

Application September 15, 1943, Serial No. 111,126

Term of patent 14 years

(Cl. D58—4)

To all whom it may concern:

Be it known that I, John O. Grady, a citizen of the United States and a resident of Arab, in the county of Marshall and State of Alabama, have invented a new, original, and ornamental Design for Knockdown Carrier Carton, of which the following is a specification, reference being had to the accompanying drawing, forming part thereof, wherein

Fig. 1 is a side elevation of the knockdown carrier carton constituting my new design,

Fig. 2, an end elevation, and

Fig. 3, a top plan view.

What is claimed is:

The ornamental design for a knockdown carrier carton, as shown.

JOHN O. GRADY.
